UNITED STATES PATENT OFFICE.

FRANK B. McCULLOUGH, OF INDIANAPOLIS, INDIANA.

CAKE-HANGER.

995,798.

Specification of Letters Patent. Patented June 20, 1911.

Application filed March 25, 1910. Serial No. 551,551.

To all whom it may concern:

Be it known that I, FRANK B. McCULLOUGH, a citizen of the United States, residing at Indianapolis, in the county of Marion 5 and State of Indiana, have invented certain new and useful Improvements in Cake-Hangers; and I do declare the following to be a full, clear, and exact description of the invention, reference being had to the accompanying drawings, and to the letters and figures of reference marked thereon, which form a part of this specification.

This invention relates to the class of cake hangers that are adapted to be used in bakeries whereby to hold cakes while dipping them in preparations for coating them to produce so-called icing on their surfaces, and to suspend the cakes on conveyers to be carried slowly thereby until the coating becomes dry and hardened, the invention having reference particularly to the portions of the hangers by which the cakes are hung on a horizontal bar.

In bakeries where cakes are produced on a large scale and are coated with icing or the like, the cake hangers heretofore used have been of such character that in the process of dipping the cakes into the icing solution the horizontal bar used of necessity was immersed in the solution, owing to the fact that the cakes were practically connected to the bar by various devices, with the result that the solution adhered to the bar which necessarily must have considerable area, and inasmuch as the coating must be removed from the bar and discarded after removing the completed cakes in order to thoroughly cleanse the hangers, the resulting loss in icing has been very considerable.

The object of the invention is to provide an improved cake hanger whereby the cakes may be immersed in the coating solution without necessitating the immersion of the supporting horizontal bar, and to provide an improved hanger that will be sufficiently strong for the purpose and yet be extremely thin in all portions thereof that of necessity must be immersed in the coating solution, so that relatively little surface is presented that can become coated and result in loss of the relatively expensive coating substance, all to the end that economy in a high degree shall result in the production of 50 iced or coated cakes.

A still further object of the invention is to provide a hanger that will be adapted

to be easily and quickly cleansed of the dried coating substance before being used, absolute cleanliness being required in such operations.

With the above-mentioned and minor objects in view, the invention consists in a supporting bar provided with a pair of arms having hooks whereby to hang the bar horizontally, and a plurality of relatively thin shanks or stems secured rigidly to the bar and provided at their ends with devices for holding cakes removably thereon; the invention consisting further in the novel parts, and combinations and arrangements of parts, as hereinafter particularly described and then pointed out in the appended claims.

Referring to the drawings, Figure 1 is a perspective view of the improved hanger as preferably constructed in which portions are broken away and omitted as being superfluous to an understanding of the invention; Fig. 2, a fragmentary side view showing the manner of securing the shanks to the supporting bar; Fig. 3, a side elevation of the preferred form of shank or stem and devices for securing cakes to the end thereof; Fig. 4, a perspective view of the preferred form of shank or stem having modified forms of cake holding devices thereon; Fig. 5, a fragmentary perspective view of a modified form of shank and cake holding device; Fig. 6, a side elevation of the preferred form of shank or stem having modified forms of cake holding devices thereon adapted more particularly for holding the larger sizes of cakes at considerable distance apart; and Fig. 7, a perspective view of the improved hanger with cakes thereon and in operative position in connection with a well known type of carrier which is illustrated by broken lines as is also the box or vessel for holding the coating solution into which the cakes are to be dipped.

Similar reference characters in the different figures of the drawings indicate corresponding elements or features of construction herein referred to.

In practically carrying out the objects of the invention a large number of cake holding devices of novel form are provided to be used in groups of convenient number, each group being connected rigidly to a bar 1 which is preferably square in cross section and has arms 2 and 2' extending from its ends in one direction at an angle thereto,

the ends of the arms having hooks 3 and 3' thereon, respectively, for supporting the bar, the arms being adapted to be held in the hands of the operator when dipping the cake in the coating solution.

The cake holding devices are all substantially alike and may be secured rigidly to the bar in various ways and are adapted in various ways to hold cakes at a considerable distance from the bar. Each cake holding device preferably comprises a collar 4 in which is a square aperture 5 to receive the bar 1. Each collar has a main shank or stem thereon that reaches out a considerable distance and is thin and narrow, but preferably comprises a broader portion 6 adjacent to the collar and relatively narrower end portion 6', the shank being tapering, and on the end of the shank are two spurs 7 and 7' extending from opposite sides of the shank, the spurs preferably extending at acute angles to the longitudinal axis of the shank. A shank extension 8 of the same thickness as the thinner portion 6' extends from the bases of the spurs and the end of the main shank in alinement with the main shank and has two spurs 9 and 9' extending from opposite sides of the end of the shank extension opposite the spurs 7 and 7', respectively. The spurs preferably are tapering throughout their length, the upper sides 10 of the spurs 7 and 7' preferably being parallel to the under sides 11 of the spurs 9, 9', the under sides 12 of the spurs 7 and 7' and the upper sides 13 of the spurs 9 and 9' therefore diverging outwardly so that when a cake is pressed onto two spurs the portion of the cake between the two spurs is slightly compressed to assist in holding the cake in position. The collars 4 are placed on the bar 1 before the arms and hooks are formed and the collars are preferably secured to the bar by means of beards 14 and 15 formed at opposite sides of the collar on each corner of the bar by pressing up portions of the metal of the bar, so that slight indentations 16 and 17 are left adjacent to the beards. The arrangement is such that the shanks and the arms extend from opposite sides of the bar 1 in one and the same plane, the shanks depending from the lower side of the bar so as to suspend the cakes.

In some cases, for coating relatively small cakes, the cake holding device is slightly modified and the smaller end 6' of the main shank has two oppositely extending spurs 18 and 18' on opposite sides thereof which may extend at right angles to the shank, the end portions of the spurs having upper beveled faces 19 and 19' respectively, near which are notches 20 and 20' whereby beards or barbs 21 and 21' are formed to assist in holding cakes thereon, but permitting the cakes to be removed without tearing off icing from their surfaces.

When it is desired to hold only one cake on each shank the devices may be modified as in Fig. 5, a thin shank 22 being composed of round wire and having one end 23 upset after driving it through a suitable aperture 70 in the bar 1, the other end of the shaft having a spur 24 thereon that has a sharp point 25 and a notch 26 near the point whereby a barb 27 is formed.

When it is desired to carry two relatively large cakes on each shank and at some distance apart so that the air may circulate freely between the cakes, the better to dry the coating, the devices for connecting the cakes to the shank are preferably modified as in Fig. 6, the thinner end portion 6' of the shank having a cross-bar 28 on its end, and the opposite ends of the cross-bar have cross-bars 29 and 29' thereon having two spurs 30 and 30' and spurs 31 and 31' respectively thereon, the cross-bars 29 and 29' preventing the cakes from being placed disadvantageously close to the shank.

It will be readily understood from the foregoing that the ends of the shanks remote from the supporting bar may be variously equipped according to expediency or fancy, for connecting the cakes or like articles to the shanks, for the purpose specified.

As clearly indicated in the drawings, the shank or stem portion of each hanger has less surface per lineal inch than the bar 1, being relatively thinner than the bar, the portion 6' that receives some of the coating while the cakes are immersed in the coating solution being extremely small in diameter as are also the spurs, so that the quantity of solution adhering to the shanks is much less than the bar 1 must retain if immersed in the solution. Each shank is many times 100 longer than its supporting collar, and preferably is longer also than either arm 2 or 2' so that the attendant after dipping operations may lift the cakes at considerable distance from his hands and dexterously shake 105 or whip off the surplus solution that may be dripping from the cakes and their immediate supporting devices into the receptacle containing the solution, and thus avoid waste of expensive material.

Referring to Fig. 7, the function of the improved cake hanger may readily be understood, the equipment of the bakery including a box or receptacle 32 for holding the coating solution, there being a shaft 33 supported above the box and having two wheels 34 and 34' thereon over which extend two conveyer chains 35 and 35', respectively, and provided on the inner sides thereof with projecting pins or lugs 36, 36', 125 to which the hooks 3 and 3' may be hung. It will be understood that the chains are of great length and are moved slowly over guide wheels, preferably in the direction indicated by the arrows.

In practical use the cakes, 37, 37', are placed on the spurs, there preferably being two cakes supported by each shank and as will be seen the cakes are at sufficient distance from the bar 1 to permit immersion of the cakes in the solution in the dipping box while the bar is kept out of the solution and therefore does not become coated, there being but relatively small surface areas of the shanks and spurs that inevitably receive coatings. After dipping the cakes the bars are hung up horizontally on the endless carrier and the cakes are carried until dry and then removed at a suitably arranged station. Then for hygienic reasons the hangers are thoroughly cleansed of coatings before being again used.

Having thus described the invention, what is claimed as new, is—

- 20 1. A cake-hanger including a plurality of series of cake-holding spurs, each series of spurs being provided with a single slender stem that is relatively longer than either one of the spurs and extends angularly therefrom, and a controlling bar secured to the free end portion of all the stems, for dipping cakes held on the spurs without immersing the controlling bar.
- 25 2. A cake-hanger including a plurality of series of cake-holding spurs, each series of spurs being provided with a single slender stem that is relatively longer than either one of the spurs and extends angularly therefrom, each stem having a collar on its free end, and a controlling bar secured to all the collars and provided with handles, for dipping cakes held on the spurs without immersing the controlling bar.
- 30 3. In a cake hanger, a cake-holding and suspending device comprising a long and slender main shank that is rod-like in form, spurs extending from one end of the thread

like shank, a shank extension projecting from the bases of the spurs in alinement with the main shank, spurs extending from the end of the shank extension, and a collar on the opposite end of said main shank, said main shank being appreciably longer in one direction only than either one of said spurs, substantially as and for the purposes set forth.

4. In a cake hanger, a cake-holding and suspending device comprising a main shank that is rod-like in form and of uniform thickness in one direction transversely, one end portion of the shank being relatively narrower than the opposite end portion thereof in the other direction transversely, said narrow end portion being approximately square in cross-section, a collar on the broader end portion of said shank, spurs on said narrower end, a shank extension projecting from the bases of said spurs in alinement with the longitudinal axis of said main shank, and spurs on the end of said shank extension, substantially as and for the purposes set forth.

5. In a cake hanger, the combination of a bar having a plurality of series of beards thereon, the bar being square in cross-section and the beards being formed on the corners of the bar integrally therewith, and collars on said bar and engaged each by a series of said beards, each collar having a long and slender stem thereon that diminishes in diameter transversely in one direction from the collar outward, and spurs on the narrower end of each of said stems.

In testimony whereof, I affix my signature in presence of two witnesses.

FRANK B. McCULLOUGH.
